PERRY L. TENNEY, OF MUNCIE, INDIANA, ASSIGNOR TO GENERAL MOTORS CORPORATION, OF DETROIT, MICHIGAN, A CORPORATION OF DELAWARE.

TRANSMISSION LOCK.

Application filed August 15, 1924. Serial No. 732,239.

This invention relates to vehicle locks, and is illustrated as embodied in a key-controlled lock for an automobile transmission.

One object of the invention is to provide a simple lock having an angularly-movable bolt for a transmission of the type having shifter forks with sliding plate-like supporting portions, one or the other of which is locked in idle position by an interlocking plate shifted transversely by the gear-shift lever. In one desirable arrangement the bolt locks one shifter fork directly, as by having a portion arranged to be turned into a notch in the edge of the fork, and locks the other fork indirectly through the interlocking plate. The interlocking plate is shown with a notch in its edge which extends inwardly and then parallel to the edge, to define a finger behind which a second locking portion of the bolt is turned to lock the plate against transverse movement while it is interlocked with the other shifter fork.

Another object of the invention is to force the driver to use his transmission lock, by having an electric switch, preferably the ignition switch, mounted on the transmission and operated by the transmission lock, so that the transmission must be locked to shut off the engine. A simple and reliable arrangement of this character is provided, the novel features being pointed out in the appended claims.

The above and other objects and features of the invention will be apparent from the following description of one illustrative embodiment shown in the accompanying drawings, in which:

Figure 1 is a horizontal section through the top of a transmission, showing the means for opening and closing the switch from the lock;

Figure 2 is a vertical section on the line 2-2 of Figure 1;

Figure 3 is a side elevation of the bottom of the key-controlled locking bolt;

Figure 4 is a top plan view of part of the interlocking plate, showing the notch for the locking bolt;

Figure 5 is a top plan view of part of one

of the shifter forks, showing the notch for the locking bolt;

Figure 6 is a section corresponding to part of Figure 1, but showing a different means for operating the switch plunger; 55

Figure 7 is a view showing the locking mechanism in plan.

The illustrated transmission is inclosed in a housing 10 with a detachable cap 12 held by screws or bolts 14 which also serve to hold a stamping or supporting plate 16 clamped at its edges between the housing and cap. The transmission is of the type in which the sliding gears are selectively shifted by one of two shifter forks 18 and 20, 60 65 slidably supported between stamping 16 and an upper stamping 22 secured thereto by bent integral fingers 24. Each shifter fork has a notch 76 in its outer edge, into one or the other of which projects the corresponding one of two downwardly-bent fingers 80, 82 on an interlocking plate 26 having a longitudinal slot 28 embracing a plunger 30 yieldingly urged by a spring 32 downwardly from a gear shift lever 34, and the lower end of which enters one of a plurality of depressions 86 in the plate 16 to thereby yieldably hold the lever in the various positions in which it may be placed. Thus the interlocking plate is moved transversely by the gear shift lever to lock the idle shifter fork and to move the lower end of the plunger 30 into one or the other of the notches 84, 84', one in each shifter fork; 70 75 the slot 28 permitting movement of the lever 80 to operate the shifter fork which is not locked. A transmission of this type is described in detail in my application No. 637-230, filed May 7, 1923.

In the edge of shifter fork 18 is a notch 40, 90 forming a 90° sector of a circle, and corresponding to a 90° segment or projection 42 on the end of a locking bolt 44 arranged for angular movement by manipulation of a key-controlled locking barrel 46. Thus projection 42 may be turned into notch 40 by a 90° turn of bolt 44, to lock the shifter fork directly against longitudinal or gear-shifting movement.

The interlocking plate 26 has a notch 48, 100

partly defined by a finger 50, so that the notch extends into the plate and then to the right (Figure 4) parallel to the edge, to define a shoulder 52 on finger 50, so arranged that when bolt 44 is turned to locking position a half-round section 54 will be turned to hook behind the shoulder to prevent transverse movement of the interlocking plate, thus locking shifter fork 20 indirectly through the interlocking plate.

Bolt 44 carries a projecting pin 56, operable when the transmission is locked to engage under the head of a plunger 58, moving the plunger against the resistance of a spring 60 to move an insulating bushing 62 between two spring fingers or brushes 64 connected respectively to a wire 66 from the battery and to a wire 68 leading to the ammeter and thence to the ignition system of the engine. When the transmission is unlocked, pin 56 is swung back, and spring 60 moves the plunger to bring between brushes 64 a conducting ring 70 mounted on the end of the insulating bushing, thus automatically closing the ignition circuit. Fingers or brushes 64 are carried by an insulating panel 72 forming one end of a housing 74 threaded into an opening in the transmission housing. It will be seen that the switch, including panel 72, housing 74, brushes 64, plunger 58, and spring 60, forms a self-contained unit which requires for assembly merely to be threaded into the opening in the transmission housing, when the transmission is unlocked, there being no joints or connections of any kind to be made.

In Figure 6 is shown an arrangement for moving the switch plunger 58 positively in both directions. Spring 60 is omitted in this arrangement, and bolt 44 carried a two-arm member 156 of resilient sheet metal, the lower arm of which is forked to engage under the head of the plunger to move it in one direction and the upper arm of which engages the top of the head to move it in the other direction. This obviates reliance on a spring for moving the plunger in one direction.

While one illustrative embodiment of the invention has been described in detail, it is not the intention to limit its scope to that particular embodiment, or otherwise than by the terms of the appended claims.

I claim:

1. A combined transmission lock and electric switch mechanism comprising, in combination, a pair of gear-shifting members, an interlocking plate cooperating with said members to prevent their movement, a key-controlled locking bolt movable to lock one gear-shifting member directly and the other through the interlocking plate, an electric switch, and means operated by movement of the bolt to open the switch when the gear-

shifting members are locked and to close the switch when they are unlocked.

2. A transmission having, in combination, a supporting plate, two reciprocating gear shifting members supported by said plate, and having each a notch so arranged that said notches may register with one another; an oscillating gear shifting lever having a spring pressed plunger at its lower end adapted to enter one or the other of said notches as said lever is moved sidewise preparatory to shifting one of the gear shifting members aforesaid; and depressions provided in said supporting plate and into which the lower end of said plunger enters, to thereby yieldably hold the same within the notch in the gear shifting member into which it is moved.

3. A transmission having, in combination, a housing with a threaded opening, a key-controlled lock including a rotatable bolt in the housing, a switch-operated part moved by the bolt, and a unitary electric switch having a supporting portion threaded into said opening, and an operating member projecting through the opening into operative relation to said switch-operating part, the switch being attachable and detachable as a unit merely by threading it into and out of the opening and being operative when in place without other connection.

4. A transmission having, in combination, two shifter forks including plate-like supporting sliding portions, an interlocking plate resting upon and shiftable transversely of the shifter forks to lock one or the other of them in idle position, the shifter forks being held against transverse movement and the interlocking plate being held against longitudinal movement, a gear-shift lever engaging the interlocking plate and adapted to move it transversely and which lever is adapted to engage the unlocked shifter fork and to move it longitudinally, and a key-controlled locking bolt constructed and arranged for angular movement to lock one of the shifter forks directly against longitudinal movement and simultaneously to lock the interlocking plate against transverse movement while the interlocking plate is in a position locking the other shifter fork against longitudinal movement.

5. A transmission having, in combination, two shifter forks including plate-like supporting sliding portions, an interlocking plate resting upon and shiftable transversely of the shifter forks to lock one or the other of them in idle position, the shifter forks being held against transverse movement and the interlocking plate being held against longitudinal movement, one shifter fork having a notch in its side edge and the interlocking plate having in its adjacent side edge a notch cut inwardly and then in a di-

rection parallel to said edge to form a hook-shaped finger, a gear-shift lever for moving the interlocking plate transversely and for shifting the unlocked shifter fork longitudinally, and a key-controlled locking bolt arranged for angular movement and having a locking part turned into the shifter fork notch by such movement to lock the corresponding fork directly against longitudinal

movement and having another locking part 10 turned by such angular movement behind the finger to lock the interlocking plate against transverse movement and thereby indirectly lock the other shifter fork against longitudinal movement. 15

In testimony whereof I affix my signature.

PERRY L. TENNEY.
